HENRY O. LOTHROP, OF MILFORD, MASSACHUSETTS.

Letters Patent No. 95,918, dated October 19, 1869.

IMPROVED MACHINE FOR MAKING WIRE FERRULES.

The Schedule referred to in these Letters Patent and making part of the same

To all to whom these presents shall come:

Be it known that I, HENRY O. LOTHROP, of Milford, in the county of Worcester, and Commonwealth of Massachusetts, have made an invention of a new and useful Manufacture of Wire Tubing for Ferrules, as well as in machines for producing the same; and do hereby declare the following to be a full, clear, and exact description thereof, due reference being had to the accompanying drawings, making part of this specification, and in which—

Figure 1 is a plan,

Figure 2, a side elevation,

Figure 3, a front end elevation,

Figure 4, a vertical central and longitudinal section, and

Figure 5, a vertical and transverse section of a machine embodying one portion of my invention.

Figure 6 is a representation of a ferrule embodying the latter portion of my invention.

The inventions which constitute the subject-matter of this patent, relate—

First, to an improved manufacture of coiled-wire tubing for ferrules, by forming an offset in each coil, in such manner that each end of the individual ferrule, when cut from the cylinder, shall present a flush or evenly-finished flat face.

Secondly, the invention relates to the construction of a machine, whereby the cylinder, provided with the offset, as described, shall be made up from the wire, and the united layers of wire soldered together, as well as to means for cutting from such cylinder a series of ferrules of equal length, the whole being in manner as hereinafter explained.

The machine I have contrived as one means of forming the above-described wire cylinder, and as illustrated in the present instance, is composed of a rotary arbor, supported in suitable bearings, and provided with a driving-pulley very much after the manner of the head-stock of a common lathe, such arbor being provided with a tapering mandrel, upon which the wire is coiled, and the cylinder made up, a beater or bunter being disposed loosely about the mandrel, and having intermittent longitudinal movements imparted to it upon such mandrel, at short intervals, a sliding cutter being arranged immediately in front of the mandrel, and operated in such manner, by instrumentalities to be described, as to cut each in regular succession from the cylinder formed upon such mandrel, as to project beyond the free end of the same, a number of sections or ferrules of a suitable length to suit the particular purpose for which they are intended.

In the drawings, before mentioned as accompanying this specification, and which illustrate my invention,

A denotes a flat tablet or table, supported by suitable standards, B B.

Upon the upper surface of such table A, I erect two supports, C C', provided at their upper part with a suitable bearing, D or D', for supporting a rotary arbor, E, such arbor having mounted upon it a driving-pulley, F, disposed about midway between the supports C C'; the arbor being still further provided with a face-plate or disk, G, fixed to it immediately in rear of its supports C, the outer face of such disk having a wiper-cam, H, formed upon it, as delineated.

The outer end of the arbor E is provided with a tapering mandrel, I, secured to it in manner as will readily manifest itself to mechanics, this mandrel being of such taper as to accommodate itself to the gradual lessening of the diameter of the cylinder, consequent upon the reduction of its temperature, as it accumulates upon the mandrel, it being first introduced to such mandrel in a heated state.

Were it not for this gradual lessening of the diameter of the mandrel, to correspond with that of the cylinder, the latter would contract so tightly about the mandrel as to adhere firmly to it, and render abortive the operation of the machine.

A tubular sleeve, a, loosely encompasses a portion of the mandrel immediately forward of the support C, such sleeve being supported about the mandrel, and prevented from revolving with it by means of a shipper, b, which surrounds it, and is pivoted to its opposite sides, the upper extremity of the shipper being pivoted to the upper part or box of the arbor-support C, while the lower end of such shipper is given a rearward horizontal bend, c, which passes through the supports C, and impinges against the outer face of the disk G, or its wiper H, before mentioned, as applied to the disk G, the shipper being maintained in contact with the disk by a spring, d, suitably applied to it.

It will be observed, by referring to the accompanying drawings, that the mandrel I has a longitudinal and axial groove, e, formed in its face, and from end to end thereof, and it will also be observed that the periphery of such mandrel is scored with a series of longitudinal and parallel teeth, f f, &c., such teeth being of about uniform depth until they approach the outer extremity of the mandrel, where they terminate at a short inclination, leaving the periphery of the mandrel at this point intact.

The teeth f f are formed in the shape of saw-teeth, the longer face of such teeth receding in a direction reverse to that of the rotation of such mandrel, and they perform an important office, to be hereinafter explained; my purpose in leaving the extreme outer portion of the periphery of the mandrel intact, being to form an even and smooth bed for the operation of the cutter, as it severs the cylinder at this point.

The revolution of the disk G, by means of its wiper, H, imparts short and quick intermittent movements

of the sleeve *a*, which I term the "beater," its purpose being to beat up the coils of wire into a compact body, as they accumulate about the mandrel.

The forward movement of the beater, in beating up the coils, also serves to advance the accumulated coils along the mandrel, while its retreat leaves room for the introduction of a fresh portion of wire.

By referring to fig. 1 of the drawings, the reader will see that the outer end of the beater *a* is formed with a slight offset or projection, *g*, the purpose of which is to cause a corresponding offset in each concentric coil of the cylinder, in order that when any one coil is cut by the cutter of the machine, at the termination of this offset, it shall leave the section thus cut with a uniformly level face, as shown in fig. 6 of the drawings, thus not only adding very much to the appearance of the ferrule, but being advantageous in other respects.

The wire of which the cylinder is composed, is first to be passed through a receptacle containing a suitable soldering-flux, and from thence conducted into and through a vessel of melted solder, the latter being situated immediately contiguous to the mandrel, in order that the solder taken up and conveyed by it shall remain in a hot and fluid state until the wire comes in contact with the last preceding coil about the mandrel, by this means producing a compact and solid cylinder.

In experimenting with my invention, I have experienced much difficulty in devising a means of insuring against slipping of the cylinder about the mandrel.

The purpose of the saw-teeth will be apparent when I state that the lessening of the diameter of the cylinder, as it contracts in cooling, forces the edges of such teeth slightly into the inner surface of the cylinder, and while permitting of its longitudinal movements upon the mandrel, prevents any rotation upon the same.

I would here call the reader's attention to the fact that the extremity of the wire, in commencing operations with the machine, is to be bent, and inserted within the groove *e* of the mandrel, by which means the wire is caused to adhere and accumulate about the mandrel until the soldered portions of such wire are brought in contact with the teeth of the mandrel.

The wire, as it is wound upon the mandrel, is necessarily in a state of tension, and, as the cooling takes place at once, it contracts so as to hug closely the tapering mandrel, thus offering all the resistance required in order to enable the beater to strike up the offset, for which I may say very little force is needed.

The cutter for severing the ferrules from the cylinder, at proper and determined intervals, consists of a sliding cross-head, *h*, carrying a suitable knife, *i*, sharp upon its lower edge, the cross-head being supported, and its vertical movements guided by means of perpendicular guides or ways, *j*, the cutting-edge of the knife, when at its highest position, being disposed above the mandrel, and in its descent reaching a point below such mandrel.

The knife is actuated by a horizontal-oscillating lever, *K*, fulcrumed at about its centre, as shown at *l*, to the upper part of a support, *m*, erected upon the table *A*, and surmounting the arbor and face-plate, and between such face-plate and the driving-pulley *f*, the forward extremity of the said lever being pivoted to the cross-head *h*, while its rear extremity is connected, by means of a rod, *n*, with a second horizontal lever, *o*, disposed at the lower part of the machine-frame, and from end to end thereof, the forward and longer arm, *p*, of this lever being pivoted to a cross-bar, *q*, making part of the standard *B*, while the rear and shorter arm, *r*, of such lever, extends a short distance in rear of the standard *B*, as shown in the drawings.

The rear extremity of the arbor *E* is disposed above that of the lever *o*, and is provided with a crank-wheel, *s*, such wheel being connected with the shorter arm *r* of the lever *o* by a connecting-rod, *t*, in such manner that a revolution of the wheel *s*, by means hereafter stated, shall cause an elevation of the free end of the said lever *o*, and of the inner end of the upper lever *K*, with a corresponding depression of the outer end of such lever, and of the knife *i*.

The movements of the knife *i* are to be so regulated or controlled as to descend and sever the ferrules after a succession of coils of wire has accumulated upon the mandrel; consequently such mandrel must complete a number of revolutions to one of the crank-wheel which actuates the knife, the intermediate mechanism connecting the arbor with such crank-wheel being susceptible of change or adjustment, in order to vary the relative number of movements of the knife and mandrel, according to the length of the ferrule to be cut by such knife.

To accomplish the last-mentioned purpose, I mount the crank-wheel *s* loosely upon the arbor, and between said crank-wheel and the rear support *C* of the head-stock, I apply a grooved disk or shipping-pulley, *u*, such pulley being disposed loosely, and sliding upon the arbor, but compelled to rotate with it, by means of an ordinary spline-and-groove connection.

Both the shipper-pulley *u* and the crank-wheel *s* are provided, upon their contiguous faces, with clutches or stops, *v*, and so that upon a close approach to each other, they shall be locked together, and describe a revolution in company; the revolution of the crank-wheel, thus produced, effecting, of course, one cutting-stroke of the knife, and severing a ferrule from the cylinder upon the mandrel.

The necessary sliding movements of the shipper *u* are effected by mechanism composed as follows:

A bent and horizontal lever or shipper, *w*, is pivoted at its bend to the top of a post, *x*, rising from the table of the machine, and to one side of the standard or support *C*, before mentioned, one end of such shipper extending into the groove of the pulley *u*, while its opposite end extends through a slot or guide, *y*, made in a lateral upright or frame, *z*, erected upon the table of the machine, and at one side of the driving-pulley of the arbor, a spring, *a'*, being applied to such upright, and pressing upon the inner side of such shipper, and serving to force it against a wiper or cam-grade, *b'*, fixed to the periphery of a spur-gear, *c'*, suitably applied to the outer extremity of the upright *z*, as shown in fig. 5 of the accompanying drawings.

The gear *c'* meshes into a second gear, *d'*, the pivot *e'*, of which is supported within an oblique slot, *f'*, made in the upright *z*, and below the orifice *y*, before mentioned, the last-mentioned gear, in turn, meshing into a pinion, *g'*, supported also upon the upright *z*, as represented, the said pinion being affixed to or making part of a third gear, *h'*, which meshes into a fourth gear, *i'*, fixed to the arbor *E* of the machine, and in close proximity to its driving-pulley.

The object in supporting the gear *d'*, of the above-mentioned train, in an adjustable manner, as explained, is to allow of the introduction of gears of different sizes in its place, for the purpose of varying the relative movements of the knife and mandrel, as before premised.

A revolution of the arbor *E*, in the direction of its arrow, causes, of course, a corresponding revolution of the gear *i'*, and a reverse rotation of the gear *h'*, which, by means of its pinion *g'*, effects a counter-revolution of the gear *d'* in a direction similar to the driving-gear *i'*, the said gear *d'*, as will be evident, imparting a rotation to the gear *c'* in the direction of its arrow.

The train of differential gears, as above described, effects seven revolutions of the cam-gear *c'* to one

revolution of the mandrel; consequently, when seven coils have projected beyond the end of the mandrel, the cutter will descend and sever them.

In practice, it will probably be found desirable to increase the number of the coils to twenty or thereabouts, in forming ferrules for paint-brushes, the principal object of my present invention being to produce ferrules for this purpose.

The operation of the train of gears upon the crank-wheel is as follows, premising, as a starting-point, the fact that the wiper *b'* has just reached the free end of the shipper *w*:

The revolution of the driving-gear *i*, from this point, forces the wiper *b'*, of the gear *c*, in contact with the free end of the shipper *w*, and, by moving such shipper upon its fulcrum, effects a rearward movement of its opposite end, by this means forcing the clutch of the pulley *u* in contact with that of the crank-wheel, and imparting a revolution of the latter in consonance with that of the arbor *E*, the length of the periphery of the wiper *b'* being such as to maintain the union of the pulley *u* and the wheel *s* until the latter has completed a revolution, and lowered the knife for the purpose of severing a ferrule from the coiled tube, when the wiper abruptly terminates, and allows the shipper to be returned (by means of its spring *a'*) to its normal position, thus breaking the connection of the pulley and wheel, and allow the latter to revolve independently upon the arbor, the lever *o*, before mentioned, thus being allowed to fall, by its own gravity, and return the knife to its highest position.

As heretofore constructed, wire ferrules have been manufactured by being first coiled about a mandrel, then removed therefrom and held in the hands of a workman while being soldered.

The time consumed in this way adds vastly to the

expense of production of such articles, and in the end does not produce so desirable an article as can be produced by means of my invention.

Another considerable item of expense by the old method, is finishing the ends of the coil of wire at each end of the ferrule. The offset, before mentioned, as constituting one feature of my invention, economizes much labor, and produces a result which cannot, by any means, be produced by the old process of manufacturing wire ferrules.

Claims.

I claim as my invention, and desire to secure by Letters Patent of the United States of America, as follows:

1. The combination of instrumentalities herein described, for making a soldered-wire ferrule, all substantially as set forth.
2. In coiling mandrels, the combination of a tapering form and grooves *ff*, with a groove *e*, all arranged and operating together, in the manner described.
3. The combination and arrangement of mechanism by which the arbor and knife are respectively operated at the time and in the manner set forth.
4. In combination with the mandrel *I*, the beater *a*, formed as described, actuated in any suitable manner, and operating as explained.
5. As a new manufacture, a ferrule made of coiled and soldered wire, having each fold of the coil formed with an offset, substantially as and for the purposes set forth.

HENRY O. LOTHROP.
